UNITED STATES PATENT OFFICE

FREDERICK J. MYERS, OF KANSAS CITY, KANSAS

HYDRAULIC RIVETING AND BENDING MACHINE

Application filed July 1, 1929. Serial No. 375,176.

The invention relates to an improved hydraulic press for driving rivets by pressure and for bending bars and plates of metal, a machine for this class of work being commonly known as a bulldozer, and when employed exclusively for riveting, a rivet press or riveting machine.

It is not new to drive rivets by hydraulic pressure, or to bend metal bars, metal plates and the like with a hydraulic press, but it has not been found practical heretofore to employ air and liquid such as oil on opposite sides of the same plunger or piston, owing to the leakage of the air over the piston or plunger into the oil, which prevents the working ram from returning to the starting point after making a working stroke.

It is very advantageous in riveting machines and bulldozers to be able to employ compressed air to drive a piston in one direction and a liquid as oil under pressure to drive the piston in the opposite direction, as will be seen from the details hereinafter set forth.

The present invention has provided an improved hydraulic press which is advantageously employed as a riveting machine for driving and setting rivets by pressure and as a bulldozer for bending metal bars, plates and the like, with the piston that operates the working ram and the piston operating against fluid as oil to create pressure, both so constructed that compressed air is employed on one side of each piston to force it in one direction and oil on the opposite side of each piston to force it in the opposite direction, very successfully with no detrimental result.

With these and other objects in view, the invention consists in the features of construction, combinations and arrangements of parts hereinafter set forth and more particularly pointed out in the appended claim, the accompanying drawings illustrating a form of the invention that has been constructed and is driving and setting rivets and bending bars and plates of metal perfectly.

In the drawings:

Fig. 1 is a plan view of the improved machine.

Fig. 2 is a view in side elevation.

Fig. 3 is a view in end elevation.

Fig. 4 is a view in elevation of the end opposite to that of Fig. 3.

Fig. 5 is an enlarged sectional view on line 5—5 of Fig. 1.

Figs. 6, 7, 8 and 9 are still further enlarged.

Figs. 6 and 7 are side and end elevations respectively of one of the pistons illustrated in Fig. 5.

Fig. 8 is a sectional view on line 8—8 of Fig. 7.

Fig. 9 is a sectional view on line 9—9 of Fig. 6.

The work table 1 is preferably of plate steel and is secured to the channel shaped frame members 2 by the rivets 3, the supporting legs 4 being secured to the frame members by the rivets 5.

The cylinder 6 is provided with the integral lugs 7 by which the cylinder is secured to the frame members 2 with the bolts 8. One end of the cylinder 6 is closed by the cylinder head 9 which is secured to the cylinder by the bolts 10, while the opposite end of the cylinder is closed by the cylinder head 11, secured thereto by the bolts 12.

Projecting from the cylinder head 11 and as shown integral therewith is the hydraulic pressure generating cylinder 13 which is formed with the upwardly disposed branch pipe 14 terminating in the flange 15.

Secured to the table 1 by the rivets 16 is the hydraulic ram cylinder 17 which is provided with the downwardly disposed branch pipe 18 terminating in the flange 19.

The flanges 15 and 19 are companion flanges and are separated only by the gasket 20, the bolts 21 securing them rigidly together and making them tight against leakage of fluid under high pressure within the pipes and the cylinders 13 and 17.

Within the cylinder 6 is the reciprocating piston 22 which can be driven from end to end of the cylinder by compressed air and tight against perceptible leakage by the piston in either direction.

Secured rigidly in the piston 22 is the tu-

bular piston rod 23 which projects within the hydraulic generating cylinder 13, is shouldered at 24 and slightly reduced in diameter, and has the stud bolt 25 secured tightly within the projecting end thereof.

Fitting the reduced diameter of the tubular piston rod 23 formed by the shoulder 24 and bearing against the shoulder and held rigidly by the nut 26 is the hydraulic piston for generating pressure, comprising the duplicate ring shaped collars 27, the duplicate packing cups 28 preferably of leather and the packing cup separator 29.

The packing cup separator 29 is circular in shape and provided with the external annular groove 30, the internal annular groove 31, the annular flanges 32 to bear against the ring shaped collars 27 so that any shrinkage of the packing cups 28 will not permit the separator 29 to move to and fro on the tubular piston rod 23, and is perforated with the radially disposed holes 33.

The tubular piston rod 23 is perforated with the radially disposed holes 34 which communicate through the internal annular groove 31 and holes 33 to the external annular groove 30 so that any leakage of fluid as oil or compressed air over either of the packing cups 28 will pass to the external groove 30 and through the holes 33 to the internal groove 31 and through the holes 34 to the interior of the tubular piston rod 23.

Telescoping into the tubular piston rod 23 sufficiently tight to prevent perceptible leakage is the escape tube 35 which projects through the cylinder head 9 and is secured thereto by the ordinary pipe bushing 36.

It will be understood from the foregoing that compressed air and the like when admitted to the cylinder 6 between the piston 22 and the cylinder head 9, in the event it leaks over the escape tube 35 to the interior of the piston rod 23 will pass out through the escape tube 35 to the atmosphere; and any air admitted between the piston 6 and the cylinder head 11 and into the pressure cylinder 13 which may leak over the adjacent packing cup 28 will escape through the piston rod 23 and escape tube 35 to the atmosphere, and should oil leak over the packing cup 28 adjacent the nut 26 it will escape in the same manner.

Within the hydraulic ram cylinder 17 and projecting therefrom is the rod shaped ram 37 working through the packing 38 and packing nut 39, the inner end of the ram being reduced in diameter forming the shoulder 24A and has the stud bolt 25A screwed tightly within the inner end thereof.

Mounted on the reduced diameter of the ram 37 formed by the shoulder 24A and held rigidly against the shoulder by the nut 26A is the hydraulic ram piston comprising the duplicate collars 27A, the duplicate packing cups 28A and the packing cup separator 29A,

the piston being a duplication on a larger scale of the hydraulic pressure piston which comprises the collars 27, packing cups 28 and separator 29.

The ram 37 is provided with the longitudinally disposed hole 40, the radially disposed holes indicated at 41 and communicating with the hole 40 and through the packing cup separator 29A, and the radially disposed holes 42 forming an exit for any oil and compressed air and the like that may leak over either of the packing cups 28A.

Secured to the table 1 by the bolts 43 passing through the slots 44 and adjustable along the slots, is the work rest 45.

The ordinary four way cock 46 is located adjacent the cylinder 6 and has connected therewith the compressed air supply pipe 47, the pipe 48 employed for compressed air exhaust, the pipe 49 leading to and communicating through the cylinder head 9, the pipe 50 leading to and communicating through the cylinder head 11 and the branch pipe 51 leading from the pipe 50 to the hydraulic ram cylinder 17 and communicating to the interior thereof between the hydraulic ram piston comprising collars 27A, packing cups 28A and the packing 38, the pipe 51 always being subject to air pressure or open to exhaust simultaneously with the pipe 50.

The four way cock 46 is operated by the handle 52 and it will be understood that all pipes leading from the cock may be closed, and that when the pipe 49 is opened to admit compressed air to the cylinder 6 through the cylinder head 9, the pipe 50 is open to exhaust from the cylinder through the cylinder head 11, and as air is admitted through the pipe 50 the pipe 49 is open to exhaust.

The hole 53 is provided to fill the branch pipes 14 and 18 and so much as is necessary of cylinders 13 and 17, and the screw plug 54 closes the hole when the machine is in operation.

The radially disposed hole 55 is for the attachment of working tools which are of common and well known form and construction.

From the foregoing it will be understood that with the supply pipe 47 supplied with compressed air the handle 52 of the four way cock 46 may be manipulated and the piston 22 reciprocated from end to end of the cylinder 6, and that the hydraulic pressure piston comprising rings 27, packing cups 28 and packing cup separator 29 will follow the movement of and move with the piston 22.

When the piston 22 is in the position shown in Fig. 5 the ram 37 is extended as shown in the same figure and when the piston 22 is in the opposite end of the cylinder 6 the ram 37 is withdrawn into the cylinder 13 as shown in Fig. 1, as the piston 22 is moved from the position shown in Fig. 5 to the opposite end of the cylinder 6 the compressed air from

the pipe 50 fills the pipe 51 and the space in the cylinder 13 between the hydraulic ram piston 27A, 28A and 29A, and the packing 38 and forces and retains the ram piston against the oil contained between the two hydraulic pistons.

Any compressed air that may leak over the packing cup 27 adjacent the cylinder 6 will pass out through the tubular piston rod 23 and escape tube 35 to the atmosphere, and should any oil leak over the companion packing cup 27 it will pass out with the air.

Any compressed air that may leak over the packing cup 27A adjacent the packing 38 will pass out through the hole 40 and hole 41 to the atmosphere, and should any oil leak over the companion packing cup 27A it will pass out with the air.

The present disclosure illustrates and describes a hydraulic press that has operated perfectly for several weeks with a single replenishing of the oil between the hydraulic pistons.

What I claim as new, and desire to secure by Letters Patent, is:—

In a hydraulic riveting and bending machine, a main cylinder with a piston therein operated by compressed air, a closing cylinder head on one end of said cylinder, the opposite end of said cylinder closed by a cylinder head provided with an elongated hub forming a hydraulic intensifying pressure cylinder opening into said main cylinder, a piston in said pressure cylinder presenting the cupped side of a hydraulic packing cup in each direction of the length of said cylinders, a ring between said packing cups provided with an external annular groove and an internal annular groove and a radially disposed hole connecting said grooves; in combination with a hollow piston rod connecting said pistons and provided with a hole connecting with said internal annular groove, and a tube secured in said closing cylinder head and telescoping into said piston rod and forming communication from said annular grooves to the exterior of said cylinders.

FREDERICK J. MYERS.
